UNITED STATES PATENT OFFICE.

GILBERT LAWRENCE SUMMERS, OF NOTTINGHAM, ENGLAND, ASSIGNOR TO WILLCOX & GIBBS SEWING MACHINE CO., OF NEW YORK, N. Y., A CORPORATION OF NEW YORK.

NEEDLE-THREAD PULL-OFF MEANS.

Application filed July 29, 1920. Serial No. 399,709.

To all whom it may concern:

Be it known that I, GILBERT LAWRENCE SUMMERS, subject of the King of Great Britain, and resident of Nottingham, England, have invented new and useful Improvements 5 in Needle-Thread Pull-Off Means, which invention is fully set forth in the following specification.

This invention relates to slack thread pull-off means for sewing machines. Although 10 designed especially for use with the machine known commercially as the Willcox & Gibbs Sewing Machine Company's "Flatlock machine," shown, for example, in the patents to 15 A. A. Merritt, No. 1,041,652, dated October 15th, 1912, "sewing machine," and Garret B. Osterhout, No. 1,134,482, dated April 6th, 1915, "rotary take-up," the pull-off means of 20 this invention are not restricted to use with any particular type or make of sewing machine.

In forming a so-called interior or closed-end seam, such as those on the sides of ladies' underwear begun at a point relatively distant 25 from the edge of the material, it is important that the formation of perfect stitches should begin with the very first stroke of the needles, because missed or imperfect stitches, even at the start of such a seam, result in marred appearance and defective work. In forming such interior 30 seams with the aforesaid Flatlock machine, some operatives have experienced missed or malformed stitches at the beginning of the seam. The probable cause is that in starting 35 or preparing to start the seam, the somewhat lengthy thread-ends ordinarily left at the finish of a preceding operation are severed by the blades of the trimmer mechanism at the first stitch-forming operation of the parts, thus leaving only short lengths of 40 the needle-threads beyond the eyes of the needles inadequate to enable the pressure of the presser-foot to grip and anchor said thread-ends against the back-pull imposed 45 thereon as the needles descend to pull more needle-thread through the tensions and form needle-thread loops through the work to be entered by the loopers. Such failure to hold 50 the needle-thread ends, and the consequent failure to form needle-thread loops for the

looper-threads, result in one or more missed or imperfect stitches before the formation of perfect stitches begins.

The principal object of this invention is 55 the provision of automatically operating pull-off means which will overcome the aforesaid difficulties by providing slack in the needle-threads between the tension means and the eyes of the needles sufficient to accommodate the down-stroke of the needles in beginning a seam without imposing back-pull upon said threads sufficient to draw the relatively short ends thereof down through the work. In operating a sewing machine, 60 such as the aforesaid "Flatlock" the operator, in making ready to begin an operation of the machine at the closed end of a seam, unlocks the needle-threads from the looper threads. This is accomplished by rotating 65 the machine, as by hand manipulation, in its normal direction until the needles are at their lowest point through the work-plate, and then rotating the machine in the reverse direction one-half a revolution or until the needles are at their highest point above the work-plate. Another object of this invention is to take advantage of such unlocking manipulation or reverse rotation to automatically actuate thread pull-off means to 70 provide the aforesaid desired slack in the needle threads available to the needles in beginning a seam at its closed end. Another object is to provide thread pull-off means which will be inoperative upon the thread 75 while the machine is rotating in normal direction, but which upon the aforesaid reverse rotation of the machine will promptly and automatically pull sufficient thread from the source of supply and past the tension 80 means to supply the desired slack in advance of the needles when the machine is thereafter operated to begin a seam. Another object is to mount such pull-off means upon and to travel with a rotating part of the machine, 85 such as a rotary take-up. Another object is the provision of thread pull-off means which can be readily and inexpensively applied to existing machines such as the aforesaid Flatlock machine.

The aforesaid and other objects and advantages attained by the invention will be

more fully understood from the following detailed explanation with reference to the accompanying drawing illustrating what is now believed to be the preferred embodiment of the invention as applied to a machine of the character of the aforesaid Flat-lock machine.

In said drawing—

Figs. 1 and 2 are vertical sectional views 10 through a portion of a sewing machine having pull-off means of this invention applied to a rotary take-up of the machine, said figures showing the position of parts when the needles are down and up respectively;

15 Fig. 3 is a detail perspective of the pull-off means;

Fig. 4 is a detail elevation showing one 20 position of the pull-off means with respect to the needle threads in the forward rotation of said means;

Fig. 5 is a view similar to Fig. 4 showing the action of the pull-off means in beginning to grip the needle threads upon reverse rotation of said means;

25 Fig. 6 is a side elevation corresponding to Fig. 5; and

Fig. 7 is a front elevation of the rotary take-up with the pull-off means applied thereto.

30 10 is a part of the bridge portion of the frame work of a sewing machine of the type illustrated in the aforesaid Merritt patent; 11 is a bracket mounted on said bridge portion and supporting a thread guide 12 and 35 tension disks 13 for a cross-thread 14. A thread guide 15, tension plates 16 for four needle threads 17, and five thread guiding hooks 18, for the four needle threads and the cross thread respectively, are also mounted on the bracket 11.

40 At 19 there is shown a second set of thread guiding hooks mounted on the bridge portion 10, one for each of the threads respectively, from which hooks the four needle threads 17 pass to thread guiding openings 20 on the head of the machine (only a portion of which head is shown in Figs. 1 and 2), thence through thread guiding openings 21 at the lower end of the needle bar to the four needles 22 respectively. The dotted line 23 in each of Figs. 1 and 2 indicates the approximate position of the upper surface of the throat plate of the machine, these two views, as before stated, showing the relative positions of the parts at different stages of the movement thereo^f in the stitch forming cycle. 25 is a horizontal take-up shaft suitably journaled in the frame-work of the machine. It is shown in this particular instance as carrying a double take-up fixed upon the shaft by a set-screw 26.

45 One cam portion 32 of said take-up, between flanges, disks or plates 28 and 29, is adapted to act upon the cross-thread 14, and another cam portion 34 of 50 said take-up, between the flanges or disks

29 and 31, is adapted to act upon the four needle threads 17. The threads pass over the take-up between the thread guiding hooks 18 and 19 before mentioned.

The cam portion 34 has a flattened surface 36. 35 is an adjustable extension of cam 34. Part 35 has a nose 39 at one end and a foot 39' at its other end contacting the flat face 36. A screw 37 countersunk in part 35 secures it to part 34. An adjusting screw 38 countersunk in a screw-threaded opening in the adjustable cam part 35 bears at its inner projecting end against the end of the surface 36 of part 34. When it is desired to adjust the take-up to give greater action upon the needle threads, the set screw 37 is first loosened and the adjusting screw 38 then turned to move the adjustable cam part 35 outwardly to the desired extent and the set screw 37 then again tightened. To lessen the action of the take-up upon the needle threads, this manipulation of the parts is reversed. The parts thus far referred to in the detailed description are similar to corresponding parts illustrated 90 and described in the aforesaid Osterhout patent.

In the embodiment of the pull-off means of the present invention shown in the drawing, said means comprise four slightly curved parallel fingers, hooks or prongs 40, 41, 42 and 43, preferably formed integral with a plate 44 which fits in a recess 45 of nose 39 of take-up 35. Two screws 46, 46, secure the plate in said recess. The fingers are arranged in pairs; thus fingers 40 and 41 constitute one pair and 42 and 43 another pair, the fingers of each pair being separated by a narrow slot flaring at its outer end where the pointed ends of the fingers diverge. In the position of the needle threads and fingers shown in Fig. 4 (and approximately the same positions of Figs. 1 and 3) the right-hand needle thread lies at the right of finger 43 with the point of said finger curving to the right over said thread, the third thread from the right being similarly positioned with relation to finger 41; the second thread from the right lies at the left of finger 42 with the point of said finger curving to the left over said thread, the thread at the extreme left being similarly positioned with relation to finger 40; and the four threads rest in guide notches 50 respectively of plate 44. With the sewing machine running in its usual or normal direction, that is forward, and the take-up and pull-off fingers rotating in the direction of the full-line arrows of Figs. 1 and 4, said take-up makes one rotation for each stitch-forming stroke of the needles and in thus tightening each stitch also pulls thread for the next stitch of each needle from the source of thread supply and past the tension plates, said fingers in such forward rotation 130

of the machine passing the threads without any pull-off action thereon. But when the operator, preparatory to commencing to sew from the closed end of a seam, manipulates 5 the machine to unlock the needle threads from the looper threads—by first bringing the machine to rest with the needles in their lowest position and the fingers projecting between the needle threads, as shown in Fig. 1, 10 and then rotating the machine one-half a revolution in reverse direction until the needles are in their highest position as shown in Fig. 2,—the pull-off fingers are brought into action. The reverse rotation of the 15 pull-off means or fingers, in the direction of the dotted line arrow Figs. 2 and 5, causes the points of each pair of fingers to engage the corresponding pair of threads and to deflect and crowd said threads into the slot between 20 the fingers until by the further reverse rotation a thread is wound around each finger and drawn to the position shown in Fig. 2 when the needles have reached their uppermost position. A surplus of the needle threads 25 is thus drawn through the tension plates and retained in the slots and around the fingers, the length of each thread so drawn past the tension plates being considerably in excess of the length of said thread drawn past said 30 tension plates by a corresponding forward rotation of the pull-off means. Fig. 5 shows the action of the fingers as they begin to crowd the threads into the slots; in Fig. 2 the threads are at the inner ends of the slots. 35 In this manner surplus of needle threads is supplied and controlled until after the goods have been correctly placed and the presser-foot lowered. When the machine is started the surplus of needle threads is immediately 40 liberated from the pull-off fingers in sufficient quantity to ensure perfect stitches from the commencement of the seam.

What is claimed as new is:—

1. In a sewing machine, the combination 45 with stitch-forming mechanism including one or more needles, of needle-thread pull-off means actuated by reverse rotation of the machine only to pull off needle-thread from its source of supply for the needle or 50 needles in subsequent operation of the machine.
2. In a sewing machine, the combination 55 with stitch-forming mechanism and thread-tensioning means, of thread pull-off means actuated by reverse rotation of the machine only to pull thread past the tensioning means and available to the stitch-forming mechanism in subsequent operation of the machine.
3. In a sewing machine, the combination 60 with stitch-forming mechanism, including one or more needles, and thread-tensioning means, of thread pull-off means actuated by reverse rotation of the machine only to pull

needle-thread past the tensioning means and 65 available to the needle or needles in subsequent operation of the machine.

4. In a sewing machine, the combination 70 with stitch-forming mechanism, including one or more needles, of rotatable needle thread pull-off means rotated by reverse rotation of the machine and acting only in such reverse rotation to pull off needle-thread from its source of supply for the 75 needle or needles in subsequent operation of the machine.

5. In a sewing machine, the combination 80 with stitch-forming mechanism and thread-tensioning means, of rotary thread pull-off means adapted to operate only upon reverse rotation of the machine, and driving connections actuating said pull-off means upon reverse rotation of the machine to pull thread past the tensioning means and available 85 to the stitch-forming mechanism in subsequent operation thereof.

6. In a sewing machine, the combination 90 with stitch-forming mechanism, including one or more needles, and thread-tensioning means, of rotary needle-thread pull-off 95 means adapted to operate only upon reverse rotation of the machine, and driving connections actuating said pull-off means upon reverse rotation of the machine to pull needle-thread past the tensioning-means and 95 available to the needles in subsequent operation thereof.

7. In a sewing machine, the combination 100 with stitch-forming mechanism and thread-tensioning means, of rotatable thread pull-off means inactive upon the thread in the normal running of the machine, and means rotating said pull-off means to pull thread past the tension means upon reverse rotation 105 of the machine and available to the stitch-forming mechanism.

8. In a sewing machine, rotary pull-off means adapted when rotated in one direction 110 by reverse rotation of the machine to engage and pull the thread from the source of supply and when rotated in the other direction by forward rotation of the machine to release said thread and thereafter remain inactive upon the thread until again rotated in the direction first named, and driving connections for rotating said pull-off means.

9. In a sewing machine, the combination 115 with stitch-forming mechanism, including one or more needles, and thread-tensioning means, of rotary needle-thread pull-off means adapted when rotated in one direction 120 by reverse rotation of the machine to engage and pull the needle thread or threads from the source of supply and past the thread-tensioning means and when rotated in the other direction by forward rotation of the machine to release said thread and thereafter remain inactive upon the thread until 125

- again rotated in the direction first named, and driving connections for rotating said pull-off means. 65
10. In a sewing machine, the combination 5 with stitch-forming mechanism including one or more needles, thread-tensioning means, and a rotary needle thread take-up, of needle thread pull-off means comprising fingers on said rotary take-up adapted to 10 engage and pull the needle-thread or threads from the source of supply and past the tensioning-means when the take-up rotates in one direction and to release and remain inactive upon said thread when the 15 take-up rotates in the other direction. 70
11. In a sewing machine, the combination with stitch-forming mechanism, of rotatable thread pull-off means inactive upon the thread in the normal direction of running 20 of the machine but rotated upon reverse rotation of the machine to pull thread from its source of supply available to the stitch-forming mechanism in subsequent stitch-forming operation thereof. 75
12. In a sewing machine, the combination 25 with stitch-forming mechanism, of thread pull-off means inactive in rotation of the machine in normal direction but operating upon rotation of the machine in reverse direction to pull thread from the source of 30 thread supply and available to the stitch-forming mechanism in subsequent operation thereof. 80
13. In a sewing machine, the combination 35 with stitch-forming mechanism including one or more needles, of rotatable needle thread pull-off means inactive in rotation of the machine in normal direction but operating automatically upon rotation of the machine in reverse direction to pull needle thread from the source of supply thereof and available to the needle or needles in subsequent stitch-forming operation of the stitch-forming mechanism. 85
14. In a sewing machine, the combination 40 of stitch-forming mechanism, of means operating automatically upon rotation of the machine in one direction to pull stitch-forming thread from its source of supply, and means operating automatically only upon rotation of the machine in the other direction to pull stitch-forming thread from its source of supply. 90
15. In a sewing machine, the combination 45 of stitch-forming mechanism including one or more needles, of means operating automatically upon rotation of the machine in normal direction to pull needle thread from its source of supply, and means operating 50 automatically only upon reverse rotation of the machine to pull needle thread from its source of supply. 95
16. In a sewing machine, the combination 55 of stitch-forming mechanism, of a rotary thread pull-off means rotating with the take-up to pull stitch-forming thread from its source of supply in one direction only of rotation of the take-up. 100
17. In a sewing machine, the combination 60 of stitch-forming mechanism, of a rotary take-up for stitch-forming thread, means rotating with the take-up to pull stitch-forming thread from its source of supply in the reverse direction of rotation but not in the normal direction of rotation of the take-up. 105
18. In a sewing machine, the combination 65 with stitch-forming mechanism, of a take-up for stitch-forming thread, and means movable with said take-up to pull stitch-forming thread from its source of supply in one direction only of operation of the machine. 110
19. In a sewing machine, the combination 70 with stitch-forming mechanism, of thread pull-off means actuated by both forward and reverse rotation of the machine, said means being inactive upon the stitch-forming thread when the machine is rotated in forward direction but acting when the machine is rotated in reverse direction to pull said thread from its source of supply and available to the stitch-forming mechanism in subsequent stitch-forming operation thereof. 115
20. In a sewing machine, the combination 75 with stitch-forming mechanism, of thread pull-off means acting in the forward rotation of the machine to pull thread from the source of supply for the formation of stitches, and thread pull-off means acting in the reverse rotation of the machine to pull from the source of supply a greater length of thread than is pulled therefrom by the first named pull-off means by a corresponding forward rotation of the machine. 120
21. In a sewing machine, the combination 80 with stitch-forming mechanism, of thread pull-off means operable to pull thread from its source of supply both upon forward and reverse rotation of the machine, said pull-off means acting to pull a greater length of thread from the source of supply on reverse rotation of the machine than on forward rotation thereof. 125
22. In a sewing machine, the combination 85 with stitch-forming mechanism, of rotary thread pull-off means operable in both directions of rotation thereof to pull thread from the source of thread supply, said pull-off means acting to pull greater length of thread from the source of supply in one direction of rotation of said means than in the other direction of rotation thereof. 130
23. In a sewing machine, the combination 90 with stitch-forming mechanism and thread-tensioning means, of rotary thread pull-off means, and driving connections actuating said means to pull from the source of supply past the tensioning means thread

in excess of the amount of thread drawn from said source of supply and past the tensioning means for each stitch in the normal running of the machine.

- 5 24. In a sewing machine, the combination with stitch-forming mechanism including one or more needles and thread-tensioning means, of rotary needle-thread pull-off means, acting to pull needle-thread past the

tensioning means upon both the forward and reverse rotations of the machine and operating in said reverse rotation to pull greater length of such thread past the tensions than in forward rotation.

In testimony whereof I have signed this 15 specification.

GILBERT LAWRENCE SUMMERS.
